SELF-LOADING DEVICE FOR SHAKER CONVEYERS

William W. Sloane, Chicago, Ill., assignor to
Goodman Manufacturing Company, Chicago,
Ill., a corporation of Illinois

Application June 15, 1950, Serial No. 168,278

5 Claims. (Cl. 198—220)

1

This invention relates to improvements in self-loading devices for shaker conveyors of the type utilized for picking up and transporting loose material, such as coal, salt, rock or the like.

One of the principal objects of this invention is to afford a construction for swivelling the pick up end of a shaker conveyor and to derive power from the movement of shaker conveyor to swivel the pick up end of the shaker conveyor.

According to the present invention use is made of the reciprocating movement of the shaker pan line to drive a pump supplying pressure fluid to a pair of fluid pressure motors mounted at the pivoted end of the swivel trough section of an articulated shaker conveyor, the fluid pressure motors driving winding drums for cables which are trained around suitable guide sheaves at the forward end of the swivel trough, and which are anchored on each side of the swivel trough at points remote therefrom.

Another important object of the invention comprehends the provision of centering means for the base supporting the articulated portion of the shaker conveyor, and a pair of jacks cooperating with the centering means and adapted to be operated by fluid pressure derived from the movement of the shaker conveyor, the jacks thrusting against the mine roof and holding the base of the articulated portion of the shaker conveyor in position.

The present invention is an improvement over the devices shown in Bergmann Patent 2,425,078, Sloane Patent 2,433,961 and Bergmann Application Ser. 118,046, filed September 27, 1949 and now abandoned, Self-Loading Devices for Shaker Conveyors.

Other important objects and features of the invention will be apparent from a study of the following specification taken with the drawings which together illustrate a preferred embodiment of the invention and what is now considered to be the best mode of applying the principles thereof. While the invention is described in terms of a preferred embodiment its scope is intended to be limited only by the terms of the appended claims.

In the drawings:

Fig. 1 is a plan view of the articulated portion of a shaker conveyor showing the forward swivel trough and the feeder trough nested therein, and showing the base plate supporting the articulated section together with the fluid pressure devices for swivelling the forward swivel trough and for holding the base plate and articulated portion in position;

2

Fig. 2 is a side elevation view of the shaker conveyor shown in Fig. 1;

Fig. 3 is a section taken along the line 3—3 of Fig. 1, the holding jacks for the shaker conveyor and the fluid pressure producing device being shown in front elevation;

Fig. 3a is a fragmentary perspective view showing certain of the parts provided for centering the base plate between the limits of forward and backward movement of the reciprocable pan line;

Fig. 4 is a detailed partly sectional and partly elevational view of one of the holding jacks of Figs. 1 to 3, the jacks being shown in lowered position;

Fig. 5 is a front elevation of the jack of Fig. 4 in raised position;

Fig. 6 is a schematic diagram showing the fluid pressure apparatus associated with the mechanism of Figs. 1 to 5;

Fig. 7 is a longitudinal sectional view through a relief or limit valve for limiting the swivelling movement of the swivel trough shown in Figs. 1 and 2;

Fig. 8 is a longitudinal sectional view through a control valve for controlling the direction of swivelling movement of the swivel trough shown in Figs. 1 and 2; and

Fig. 8a is a fragmentary sectional view of Fig. 8 taken along the line 8a—8a.

Referring now particularly to Figs. 1 and 2 of the drawings, the invention is shown as being embodied in an articulated shaker conveyor which includes an extensible trough 10 having a shovel (not shown) at its forward end, which preferably supports the forward end of the extensible trough 10 on the ground. The rear end of the extensible trough 10 is supported above the ground on a ground engaging shoe 11 by

means of a pair of laterally spaced supporting legs 13, 13 which are pivoted to the shoe 11 and extend upward therefrom along the outer sides of a reciprocating swivel trough 14 within which the extensible trough 10 is nested. The supporting legs 13, 13 are suitably secured at their upper ends to the rear end portion of the extensible trough 10 by bearing plates 16, 16 extending along the upper outer sides of the extensible trough 10. The bearing plates 16, 16 are adapted to be engaged by friction-grip blocks not shown, of a feeding mechanism, also not shown, at the forward end of the swivel trough 14, in a manner well known to those skilled in the art.

The reciprocating swivel trough 14 is connected to and reciprocably driven from the shaker

conveyor trough line through an articulated trough connection indicated generally by the number 17, which is so arranged as to form a means for controlling the lateral movement of the extensible trough 10 and the swivel trough 14, and to provide for the continuous flow of material along the extensible trough and the swivel trough to the outby end of the trough line, when the reciprocating and extensible troughs are in various positions of lateral displacement with respect to the trough line. Such a swivel is clearly shown and described in Sloane Patent 2,433,961, issued January 6, 1949, for Improvements in Shaker Conveyors. The details of construction of the articulated trough connection 17 form no part of the present invention except for the details necessary to explain the construction and embodiment of the present invention.

The articulated connection 17 includes a support base 18 adapted to be held in place by laterally spaced hydraulic jacks 19 during operation of the conveyor. A plate 21 is adapted to overlie the base plate 18 and to have a limited restrained movement with respect to the base 18 in a vertical direction as more clearly described and claimed in Sloane Patent 2,433,961. The plate 21 thus provides a yieldable support for a pair of spaced guideways 22 for a floating frame 23 having guide rollers 24 mounted on each side thereof. A shaker trough pan 25 having a curved forward end 27 is connected by a plurality of connecting bosses 28 to the floating frame 23.

An intermediate trough section 29 having a flared end 31 adapted to nest within the curved end 27 of the trough pan 26 is connected to swivel on a pivot 32 on the floating frame 23. The intermediate trough section 29 is likewise curved as at 33 at its receiving end and is pivoted at 34 to the outby end 36 of the swivel trough 14 which is nested within the curved end of the intermediate trough 29.

A support 37 is riveted at 40 to the swivel trough 14 and underlies both the swivel trough 14 and the intermediate trough 29. The support 37 extends toward the outby end of the articulated connection 17 and is provided with a pair of V-guides 38.

A swivel frame 39 which extends toward the swivel trough 14, and which underlies the support 37, is pivoted at its outby end on a hub 41 formed on the plate 21. The swivel frame 39 is provided with a pair of spaced V-rollers 42 which ride in the V-guides 38, and which are so spaced as to provide for swiveling movement of the swivel frame 39 with respect to the support 37, while the support 37 is reciprocating with the trough section.

The details of such construction are more clearly shown in the aforementioned patent to William W. Sloane, No. 2,433,961, and in the aforementioned application of Ernst R. Bergmann, Serial No. 118,046, filed September 27, 1949.

The jacks 19 which are arranged to hold the base 18 in position consist of a pad 43 secured to the base 18 in any convenient manner and having a recess 44 for a centering ball 46 upon which rests a recessed cylinder head 47. The cylinder head 47 is flanged and is bolted to a cylinder 48 having a flange 49. A plurality of aligning bolts 51 cooperating with springs 52 and keeper washers and nuts 53 hold the cylinder 48 and cylinder head 47 against the ball 46. As shown with reference to Fig. 5, the bolt 51 has a

head 54 which is self-aligning with respect to the pad 43, as shown at 56.

The cylinder 48 has a double acting piston 57 therein having a skirt 58 which is spaced from the inner wall of the cylinder 48. The skirt 58 slides along a packing gland and sleeve 59 which is bolted to the cylinder 48. The piston 57 provides a support for an inner sleeve 61 having an end plate 62 welded thereto which is held to the piston 57 by a socket head screw 62a. A jacking pad 63 is secured by a set screw 64 to the top of the inner sleeve 61.

The jack 19 is raised by fluid pressure directed against the piston 57 from an inlet port 66 in the cylinder head 47. The jack is lowered by fluid from a port 67 in the wall of the cylinder 48, which enters a chamber 68 between the skirt 58 of the piston 57 and the cylinder 48, and which exerts pressure against a shoulder 69 of the piston 57.

As best shown in Figs. 3, 3a, 4 and 5, means are provided for automatically centering the jack-carrying base 18 with respect to panline-carrying floating frame 23 prior to raising the jacks against the mine roof. For this purpose the floating frame 23 is provided with two lateral centering ears 71, one on each side, which reciprocate with the frame 23. Each centering ear 71 is engageable with a pair of longitudinally spaced arms 72 of a bell crank 73 pivoted to lug means 74 fastened on the top side of base 18. As will be explained in the next paragraph, each bell crank 73 is adapted to rock to and from a base-centering position between two longitudinally spaced ears 76 which are mounted on the top side of plate 21. As will also be explained, each jack 19 is linked with its corresponding bell crank 73 to hold the arms 72 of the latter in a position of alignment with the ears 76 when the jack is in a "down" position (see Fig. 3). Thus, in operation, after the shovel trough has been moved forward to a new setting, and while the jacks are still in their "down" position as shown in Fig. 3, a few initial strokes of the conveyor will automatically center the base and the jacks carried thereby through the action of arms 71 engaging with bell crank arms 72.

The jacks 19 are adapted to be maintained in their raised position with the base 18 free from the effect of the movement of the ears 71 in tending to strike the arms 72 of the bell crank 73. To this end the bell crank 73 is connected by a link 77 to a bell crank 78 pivoted at 79 to the side of the gland 59. The skirt 58 retains a collar 81 which rocks the bell crank 73 to the position seen in Fig. 4 when the jack is lowered. A spring 82, connected to the link 77 at one end, and to the pad 82a at the other end, causes the bell crank 73 to rock in a counter-clockwise direction to a position as seen in Fig. 5, so that the jacks 19 are free from any influence resulting from reciprocation of the pan line, thereby minimizing the disturbance of the jacks 19 when in extending position.

Referring again to Figs. 1 and 2, fluid pressure motors 83 are provided for moving the swivel frame 39 about the pivot 41 at the same time swivelling the swivel trough 14 and the extensible trough 10. The fluid pressure motors 83 operate alternately to reel in a cable 84 which is trained around sheave (not shown) at the forward end of the swivel frame 39 and around sheaves 86. The cables 84 are anchored to oppositely disposed abutments as more clearly shown in Berg-

mann application, Serial No. 118,046, filed September 27, 1949.

As shown more clearly in Fig. 2, the fluid pressure motors 83 are connected through a gear train 87 to drive a cable drum 88 having the cable 84 wound thereon. The drum 88 is mounted on a manually operated eccentric 89 to disengage the drum 88 from the gear train 87 when desired.

A fluid pressure system is provided for supplying fluid under pressure to drive the fluid motors 83 and to supply pressure to the jacks 19. A double acting piston type pump 91 is hingedly connected to a clevis block 92 mounted on the base 18, and has a piston rod 90 connected to a walking beam 93 which pivots about a fulcrum block 94 also mounted on the base 18. The opposite end of the walking beam 93 is hingedly connected by a link 96 to a movable abutment 97 on the underside of the trough pan 27, see also Fig. 3.

Referring now to Fig. 6, the pump 91 is connected to a reservoir 98 by a supply line 99. The pump 91 is connected by a pressure conduit 101 to an accumulator 102, which stores pressure fluid delivered by the pump 91 upon reciprocation of the shaker trough pan 27. As is customary in such fluid pressure systems, fluid is bypassed by a line 103, through an unloading valve 104 and by a line 106 to the tank 98 when the pressure in the accumulator reaches a predetermined maximum value.

The operation of the jacks 19 is under the control of a valve 107 connected to the high pressure line 101 by a branching line 108. The control valve 107 is of a conventional kind and includes an operating handle, which when operated in one direction will pass fluid through a line 111 to enter the jacks 19 at the port 66 to elevate same. The jacks 19 are lowered by operating the handle 109 in the opposite direction which connects the line 111 to an exhaust line 112 to the tank 98, and which connects the line 108 to a line 113 to pass pressure fluid to the port 67.

The fluid motors 83 are under the control of a valve 114 which is actuated by valve control rod 116 which terminates at a point adjacent the feeding mechanism at the forward end of the swivel frame 39.

The control valve 114 selectively controls the operation of either of the fluid motors 83 to swivel the frame 39, the swivel trough 14, and the extensible trough 10 in either direction of swiveling movement, to reel up either of the cables 84 according to the direction of such movement.

Referring now to Fig. 8, the control valve 114 includes a valve body 116 having a bore 117 therein. The bore 117 is intersected by a pressure port 118 connected to a pressure line 119. The bore 117 is also intersected by working ports 121 and 122 respectively which flank the pressure port 118 and which are connected to intermittent pressure lines 123 and 124 to supply pressure fluid alternately to either of the fluid motors 83 or to block the pressure fluid to each when it is desired to stop the swiveling action of the swivel trough 14 and the extensible trough 10. The working ports 121 and 122 are respectively flanked by exhaust ports 126 and 127 which are connected by an exhaust line 128 to the tank 98.

A valve rod 129 having a pair of spaced lands 131 and 132 thereon is slidable in the bore 117 and controls the movement of pressure fluid

through the valve 114. The rod 129 is also slidably in a seal 133 which is held in place by a drilled end cap 134. The valve rod 129 is also provided with a shoulder 136 for spring keeper 137 which at times bears against a shoulder 138 formed on the bore 117. A portion 139 of the valve rod 129 is encircled by a return spring 141 which bottoms against a spring retainer 142 held by a pin 143. The spring retainer 142 normally bears against a shoulder 144 of an end cap 146 of the valve body 116.

The valve rod 129 is shiftable to the right against the bias of the spring 141 so that pressure fluid moves from pressure line 119 to intermittent pressure line 124 to operate the respective fluid motor 83 connected thereto. Under this condition the land 131 opens line 123 to exhaust port 126. Upon shifting the valve rod 129 to the left against the bias of the spring 141 pressure fluid passes into line 123 to operate the other fluid motor and the land 132 opens the line 124 to the exhaust port 127.

Means are provided for limiting the amount of swivelling movement of the swivel frame 39 in either direction by bypassing pressure fluid normally operating either of the fluid motors. Referring again to Figs. 1 and 2, each side of the swivel frame 39 is provided with a limit valve 147 having a valve actuator rod 148 adapted to engage a stop 149 mounted on the base 18.

Referring now to Fig. 7, the limit valve 147 includes a symmetrical valve body 151 having a pressure passageway 152 which is intersected by a bore 153. The valve body has a counterbore 154 which is intersected by port 155 connected to the supply reservoir. The counterbore 154 is provided with a ball valve 156 which at times is seated on a shoulder 157. The ball valve 156 is normally held against the seat 157 by ball retainer 158 and a spring 159 bottomed against an end cap 162. The spring 159 is guided by a stem 161 held by the end cap 162.

The valve actuator 148 is guided in a threaded thimble 163 and includes a ball valve lifter 164 of reduced diameter adapted to fit into the bore 153.

The valve 147 is connected to the pressure inlet side of each motor 83 by a line 166 to either pressure port 152. It will be understood that the opposite pressure port 152 is plugged, the valve 147 being symmetrical for right or left installations. When the actuator 148 engages the stop 149, the ball valve 156 is lifted from its seat to bypass fluid normally supplying the associated motor out the tank port 155 by line 167 which connects to the return line 128.

The spent fluid from the motor 83 passes therefrom by a line 168 connected to a drain port 169 in the valve body 151 and thence out the valve 147 by line 167. Each motor may likewise be provided with a drain line 171 to the limit valve 147.

While the invention has been described in terms of a preferred embodiment thereof, its scope and breadth is intended to be defined only by the claims here appended.

I claim as my invention:

1. In a self-leading device for shaker conveyors and in a swiveled conveyor trough line including a base which is held against movement with respect to the ground during reciprocation of the conveyor and having a reciprocably swivelable trough section connected to said base for laterally swinging movement with respect thereto; a frame mounted for slidable movement along the ground at its inby end and having an articu-

lated connection with said base at its outby end; the combination therewith of means comprising an hydraulic system including a tank and an accumulator and a pump all mounted on said base, said pump having an operating connection with said trough line and being operable upon reciprocation of said trough line for supplying fluid under pressure to said accumulator, fluid pressure operated winding devices mounted on said frame adjacent the outby end thereof and on opposite sides of said swivel trough line for swinging movement therewith, flexible draft devices wound on said winding devices, means training said draft devices from opposite sides of the inby end of said frame for laterally swinging said frame when said draft devices are anchored to laterally disposed abutments, means including a control valve and an operator therefor mounted adjacent the inby end of said laterally swingable frame for controlling the flow of pressure fluid to one or the other of said fluid motors, and valve means operable by the swinging movement of said frame to an extreme limit of travel in either direction to bypass pressure fluid normally supplying one of said fluid motors to tank.

2. In a self-loading device for shaker conveyors and in a swiveled conveyor trough line including a base which is held against movement with respect to the ground during reciprocation of the conveyor and having a reciprocably swivelable trough section connected to said base for laterally swinging movement with respect thereto; a frame mounted for slidable movement along the ground at its inby end and having an articulated connection with said base at its outby end; the combination therewith of means comprising an hydraulic system including a tank and an accumulator and a pump all mounted on said base, said pump having an operating connection with said trough line and being operable upon reciprocation of said trough line for supplying fluid under pressure to said accumulator, fluid pressure operated winding devices mounted on said laterally movable frame adjacent the outby end thereof and on opposite sides of said swivel trough section for swinging movement therewith, flexible draft devices wound on said winding devices, means training said draft devices from opposite sides of the inby end of said frame for laterally swinging said frame when said draft devices are anchored to laterally disposed abutments, means including a control valve and an operator therefor mounted adjacent the inby end of said laterally swingable frame for controlling the flow of pressure fluid to one or the other of said fluid motors, and means including a valve mounted on each side of said swinging frame cooperating with a valve actuator mounted on each side of said base for bypassing pressure fluid normally supplying one of said fluid motors to tank upon lateral swinging movement of said frame to an extreme limit of travel in either direction.

3. In a self-loading device for a shaker conveyor including a reciprocating pan line articulately connected to a swivelable trough having an extensible feeder trough section which is laterally movable with said swivelable trough and extensible and retractable with respect to said swivelable trough section, a base affording a support for said pan line and said swivelable trough for reciprocating movement thereof with respect to said base; the combination therewith of means comprising an hydraulic system including an accumulator and a pump mounted on said base, said

pump having an operating connection with said pan line and being operable upon reciprocation of said trough line for supplying fluid to said accumulator, means for centering said base upon initial reciprocation of said pan line, and a pair of oppositely disposed hydraulic jacks mounted on each side of said base and adapted to be extended by fluid pressure from said accumulator after said base has been properly centered by reciprocation of said pan line.

4. In a self-loading device for a shaker conveyor including a reciprocating pan line articulately connected to a swivelable trough having an extensible feeder trough section which is laterally movable with said swivelable trough and extensible and retractable with respect to said swivelable trough section, a base affording a support for said pan line and said swivelable trough for reciprocating movement thereof with respect to said base; the combination therewith of means comprising an hydraulic system including an accumulator and a pump mounted on said base, said pump having an operative connection with said pan line and being operable upon reciprocation of said trough line for supplying fluid to said accumulator, means for centering said base upon initial reciprocation of said pan line, comprising spaced members on said base marking the limits of travel of said pan line, a member carried by said pan line for moving said spaced members and said base to a position centering said base, a pair of oppositely disposed hydraulic jacks mounted on each side of said pan line and anchored to said base, said jack being extensible by pressure fluid, and means operable upon extension of said jacks for moving the centering means to a position where said jacks will be undisturbed by reciprocation of said pan line.

5. In a self-loading device for a shaker conveyor including a reciprocating pan line articulately connected to a swivelable trough having an extensible feeder trough section which is laterally movable with said swivelable trough and extensible and retractable with respect to said swivelable trough section, a base affording a support for said pan line and said swivelable trough for reciprocating movement thereof with respect to said base; the combination therewith of means comprising an hydraulic system including an accumulator and a pump mounted on said base, said pump having an operative connection with said pan line and being operable upon reciprocation of said trough line for supplying fluid to said accumulator, means for centering said base comprising a bell crank pivoted to said base and having a pair of spaced crank arms, a member carried by said pan line for moving said crank arms and said base to a centered position on said base, a pair of oppositely disposed hydraulic jacks mounted on each side of said pan line and anchored to said base, said jack being extensible by pressure fluid from said accumulator, and means for rocking said bell crank upon extension of said jacks for moving the centering means to a position where said jacks will be undisturbed by reciprocation of said pan line.

WILLIAM W. SLOANE.
